PROCESS FOR RECONDITIONING PERFORATED RECORD CARDS

Hermann A. Rottke, Berlin-Schlachtensee, Germany, assignor to International Business Machines Corporation, New York, N. Y., a corporation of New York

Application June 22, 1938, Serial No. 215,301
In Germany July 8, 1937

1 Claim. (Cl. 117—2)

This invention relates to a method for reclaiming perforated cards and more particularly for reclaiming perforated cards of the well known "Hollerith" type so that they may be reperforated for further use.

It is, therefore, an object of this invention to provide a method for reclaiming perforated cards by filling in the perforated areas with a suitable plastic mass so that the card may be again perforated in the same manner as an unperforated card and utilized further.

The use of perforated cards of the "Hollerith" type for controlling sorting, accounting and statistical machines is well known. In this type of accounting system, the cards are scanned by a plurality of contact brushes under an electric potential. When the brush encounters a perforation, it contacts a contact member on the opposite side of the card to cause a current to flow and effect actuation of the accumulators. The cards are usually laid out in "fields" with vertical lines separating each field. The different "fields" may represent different types of data, such as customer, date, order number, items of sale, amount, etc. It is frequently the case that a large part of a card may be perforated to represent data which is fixed or constant, whereas a small part representing one or perhaps two fields may be perforated to represent data which is variable and which, therefore, may be changed. Unless a method is devised to wipe out the perforations already existing in these fields so that new perforations representing a change in the data may be placed in that field, it would require a complete new perforation of a new card and the necessity for destroying the old one.

It was found that by using a plastic mass consisting of a chemical solution of acetone and acetyl cellulose in which methyl chloride has been dissolved for filling the perforated areas that the cards could be reperforated and used further. This solution evaporates rapidly and it was found that at normal temperature and atmospheric pressure it dried so quickly on the devices which were applying the mass that there was considerable trouble encountered in making such application of the mass to the card. In this connection even though the mass when applied to the card penetrated through the holes in the card, it would dry quickly and stick to the applicators and immediately pull the mass out of the perforation so that no closure was effected.

It was also found that the mass could not be generally spread clear across the card, because the mass would leave beads along the edge. For these reasons special measures had to be taken to effect a suitable method for applying this mass and it was found that, if the mass was applied to the card under a substantial vacuum by means of a brush-like wick and applied within the edges

of the card, the closure of the perforations and reclamation of the cards were successful.

Further objects of the instant invention reside in any novel feature of construction or operation or novel combination of parts present in the embodiment of the invention described and shown in the accompanying drawings whether within or without the scope of the appended claim and irrespective of other specific statements as to the scope of the invention contained herein.

In the drawings:

Fig. 1 shows a front elevation of a mass applying device and a drying device.

Fig. 2 shows a side elevation of the drying device.

Turning now to Fig. 1 the mass applying device is shown generally at A and the drying device generally at B. The applying device is diagrammatically shown and is mounted on a base 15 suitably supported by standards 2 and enclosed by means of a housing 3 having an opening 4 normally closed by an air-tight cover 5. A stack of cards 6 may be placed in a hopper 7 through the opening 4. These cards are fed from the bottom, one at a time, by means of a picker 8 connected by a link 9 to pin 10 on the wheel 11. This type of picker feed is well known in the art and may be any suitable type such as that used in the "Hollerith" type of machine, such as is shown, for example, in the patent to E. A. Ford, No. 1,684,389, dated September 18, 1928. The wheel 11 is rotated by drive shaft 12 connected thereto by means of beveled gears 13. The drive shaft 12 is connected to one side of a friction clutch 14a which is normally held in closed connection with the other clutch member 14b by means of a spring 15. The clutch member 14b is movable along a splined shaft 16 journaled at 17 and having affixed to its end a pulley 18 which

40 may be belted to a suitable motor M connected through a switch S to a suitable line supply L. The clutch member 14b is also provided with a collar 19 which is engaged by a yoke 20 pivoted at 21 and integral with an armature 22 which cooperates with a magnet 23. With the power driving the wheel 11 through the shafts 16 and 12, energization of the magnet 23 causes the clutch member 14b to disengage the member 14a and causes the wheel 11 to stop. Wheel 11 is connected to a gear 24 which drives gear trains 25, 26, 27, 28, 29, 30, 31 and 32 and has a 1:1 ratio. Gears 25, 27, 29 and 30 are connected to feed rollers which receive the card from the magazine and feed it between the rollers from left to right

55 as viewed in Fig. 1. The feed rollers may be thin disks which grip the edges of the card or they may be cylindrical rollers having a series of annular grooves which span the index point positions where the perforations lie on the cards. A reservoir 33 for containing a supply of the plastic

mass which is to be applied to the card is mounted on a bracket 34 which is pivoted at 35 and which has a projection 36 that rests on a cam 37 and is held there by virtue of a spring 38. The cam is caused to rotate by the gear train previously mentioned to rock the bracket 34 up and down. The wick 39 is mounted with one end in the reservoir of the plastic mass and is so adjusted that, when the bracket 34 is elevated by the high point of the cam, the wick will wipe the card which is under the roller 27 and, when the bracket 34 is at its lowest point of the cam, the wick will not touch the card. An opening in the case 43 is provided at 40 and is further provided with a slideable and air-tight gate member which may be raised or lowered by means of a rod 41 to open or close the opening. A suitable coupling such as a pipe coupling 42 is provided and is mounted to the case 43 of the drier generally shown at B and opens into the drier.

Another coupling 44 leading from the interior of the case 43 is provided for the purpose of attaching a vacuum pump to evacuate the air from within the drier case. With this drier case coupled tightly to the case carrying the mass applying mechanism A and with the rod 41 lifted to open the gate valve, the evacuation by means of the air pump connected to 44 will create a substantial vacuum in both the mass applying device and the drier. The drier is provided with a large drum 45 provided with a series of pockets 46 and is rotatably mounted on a shaft 47. Fixed to the shaft 47 is a pulley wheel 48 around which is wound a cord 49 having a weight 50 attached thereto which tends to rotate the drum in a clockwise direction. The periphery of the drum is provided with ratchet teeth 51 which are engaged by an escapement 52 pivoted at 53 and fixed to an armature 54. The armature is associated with a magnet 55 so that upon the energization and deenergization of the magnet the single oscillation of the escapement 52 causes the drum to rotate an angular distance equivalent to a single tooth on the periphery. There are an equal number of teeth and pockets so that the rotational advance of a single tooth presents a new pocket 46 to receive a card.

A normally open contact 56 is mounted on the casing 43 and lies in the orbit of rotation of a pin 57 which extends from the side of the drum 45. When the drum rotates one complete revolution in a clockwise direction, the pin will strike the back of the contact blade 58 to effect closure of the contacts 56. The contact 56 and the magnet 55 are connected by means of a wire to a terminal board 59 mounted on the outside of the casing and provided with a series of sockets. Movable plug wires 60 are connected from the terminal board 59 to the terminal board 61, which terminal board is connected to the magnet 23 and to a pair of contacts 62. The contacts 62 are controlled by a cam 63 which are rotated from the gear 32 so that the contacts open and close once each card feeding cycle. Contacts 62 are connected in circuit with the magnet 55 and contacts 56 are connected in circuit with the magnet 23.

The operation of the machine is as follows: The drier B is coupled to the mass applying device A and the air exhausted therefrom by suitable means. Cards are fed one by one from the bottom of the stack of cards to the feed rollers

and, as the leading edge of each card just passes the wick 39, the cam 37 causes the wick to be raised against the card and the mass applied from the reservoir 33, holding the wick against the card until just prior to the following edge of the card passing the wick, at which time the wick is lowered away from the card. The card continues to be fed through the opening of the gate at 40 and into one of the pockets 46 of the drum 45. At this time the cam 63 which operates once each card cycle causes the contacts 62 to close and open, which energizes and de-energizes the magnet 55 causing the drum to rotate one step and presenting an empty card pocket to receive the next card. These pockets merely support the cards along their outer edges. The feeding of the cards continues with each card going into a separate empty pocket and the drum continually feeding in a clockwise direction until it becomes full, at which time the pin 57 strikes the back of the blade 58 to cause contact 56 to close. The closure of contact 56 completes a circuit through the magnet 23 to disengage clutch members 14a and 14b and thereby cause the card feeding to stop. The rod 41 is then pushed down to close the gate at 40 and the drier uncoupled and rolled away by means of rollers 85 on which the drier mechanism is supported, after having been uncoupled from the vacuum pump at 44. In order to avoid the re-starting of the feed mechanism, switch S is thrown to the open position previous to the uncoupling of the drier. Air at atmospheric pressure is admitted to the drier at this time. In the meantime by means of the air-tight gate at 40, the structure and the mass within the mass applying device is being kept under a substantially low pressure. An empty drier is then moved in place and coupled to the mass applying device and to the vacuum pump, air is evacuated from the empty drier first, after which the gate at 40 is open and the process is repeated to fill the drum.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claim.

What is claimed is:

A process for reconditioning a perforated record card controlling a tabulating machine, without materially altering its original dimensions, said process utilizing a filling material comprising cellulose acetate, acetone, and methyl chloride in a plastic form and consisting of the step of applying a thin layer of said material to the surface of said card for injecting said material into said perforations, calendering said card to cause said material to fully occupy said perforations, said application and calendering being effected upon said card in a region of sub-atmospheric air pressure, and then subjecting said card to a region of normal atmospheric pressure, whereby said filling material in said perforations is urged to rapidly dry and harden.

HERMANN A. ROTTKE.
